phone and Radio Corporation, New York, N. Y.,
a corporation of Delaware

Application August 19, 1944, Serial No. 550,185

2 Claims. (Cl. 179—15)

1

This invention relates to radio multi-channel communication.

An object of the invention is to provide a method and means for simultaneously transmitting and/or receiving at least two channels of intelligence modulated according to different principles of modulation on substantially the same carrier frequency or frequency band.

A feature of the invention is the provision of means to modulate a carrier for one of the channels as a continuous wave, either by amplitude or frequency modulation and means to pulse modulate a second carrier according to some principle of time modulation. The two carriers may be mixed or intermodulated as a composite carrier before transmission or they may be transmitted at separate points and mixed in the medium of transmission.

Another feature of the invention is the provision of means for receiving the composite carrier comprising the two channels of modulation and to separate therefrom each of the two channels for reproduction. The separation of the pulse component of the carrier is effected by clipping the received energy at a level above the maximum amplitude of the continuous wave component. The separation of the continuous wave component is effected by clipping the received energy between two levels containing therebetween a substantial portion of the continuous wave and a minimum, if any, of the pulses.

The above and other objects and features of our invention will become more clearly understood upon consideration of the following detailed description to be read in connection with the accompanying drawings, in which:

Fig. 1 is a block diagram of a transmitter and a receiver according to the communicating principles of our invention;

Figs. 2 and 3 are graphical illustrations used in explaining the multi-channel communication performed by the system shown in Fig. 1; and

Fig. 4 is a block diagram illustrating a variation of the transmitter portion of the communicating system of Fig. 1.

In Fig. 1, three sources of signal energy 1, 2 and 3 are shown each coupled to a modulator. The modulator 4 with which signal source 1 is associated, may comprise any known form of amplitude modulator whereby the signal intelligence of source 1 modulates a continuous carrier wave within a given frequency band. The modulator 5 associated with signal source 2 may comprise any form of frequency modulator arranged to modulate a second continuous carrier wave according

2

to the intelligence of signal source 2 in the same given frequency band in which modulator 4 operates. The output terminals of the two modulators 4 and 5 are connected to a selecting switch 6 whereby one or the other of the continuous modulated waves of modulators 4 and 5 may be selectively applied to a coupler 7 for transmission over antenna 8.

The signal source 3 is associated with a time modulator 9 of any known form capable of displacing the pulses of a train, either produced by the modulator 9 or received from a different source, in accordance with the instantaneous values of the intelligence received from the signal source 3. The time modulated pulses of modulator 9 are applied to a radio frequency modulator 10 for pulse modulation of a carrier wave within the same frequency band in which the modulators 4 and 5 operate. If the type of pulse transmission is such that a wider band width is used than the AM or FM system, several such AM or FM systems spread throughout the pulse frequency band may be used. The pulse modulated carrier is applied to the coupler 7 where it is mixed with the selected carrier from modulators 4 and 5 for transmission. The mixing of the two carriers results in a composite carrier due to a superposition effect of the two carriers. This superposition of the two carriers is indicated by graphs 2a and 3a of Figs. 2 and 3, respectively. Graph 2a represents a composite carrier 11 resulting from the superposition of the carriers produced by modulators 4 and 10. Graph 3a represents the composite carrier 12 resulting from the superposition of the carriers produced by modulators 5 and 10. As shown, the composite carrier 11 is made up of a carrier 13 produced at modulator 4 and superimposed thereon are pulses 14 produced by the modulator 10. Likewise the composite carrier 12 is made up of a continuous frequency modulated wave 15 and pulses 14 from modulator 10 superimposed thereon.

The components of composite carrier 11 are shown to be in phase. They may, of course, occur out of phase, and in such instances one component may subtract from the other. To avoid loss of one or both components, the peak power of the pulse carrier is made greater than the peak power of the continuous carrier.

At the receiver the composite wave 11 or 12, as the case may be, is received over antenna 16 and preferably, although not necessarily at this point, reduced to an intermediate frequency by the usual R. F. and I. F. amplifier stages 17. For separation of a desired channel, the output ener-

gy of amplifier 17 is applied through a pulse clipper 18 for clipping along a level such as indicated at 19 and 19a in graphs 2a and 3a, respectively. This clipping operation is adjusted to obtain the pulse energy occurring above the maximum amplitude of the continuous wave component of the received energy. The clipper 18 may comprise any known form of clipper gate or it may be of the threshold clipping type in which case the clipped energy from graphs 2a and 3a will appear substantially as indicated in graphs 2b and 3b, respectively. Where the pulse energy occurs as shown in 2b, the pulse energy may be limited to a given amplitude by suitably biasing the detector 20 to which the pulse energy is applied from clipper 18. Such a limit level is shown at 21 in graph 2b. The pulse output of the detector 20 is then applied to a known form of time demodulator 22 depending, of course, upon the principle of the time modulation at modulator 10. By way of example only, a suitable time modulator and demodulator for time modulated pulses is disclosed in Reeves, U. S. Patent No. 2,266,401.

To obtain the intelligence of the continuous wave component of the composite carriers, the output energy of amplifier 17 is applied to a clipper gate 23 arranged to clip energy between two levels 24 and 25, as indicated in graph 2a, or levels 24a and 25a as indicated in graph 3a. Where the composite carrier is of the type shown in graph 2a, the output of clipper gate 23 is selectively applied through switch 26 to an AM-detector 27. The output of such detector is indicated in graph 2c, whereby the signal envelope of the amplitude modulated continuous wave 13 is shown at 13a together with portions of the pulses 14 as indicated at 14a. The output of the detector 27 is preferably provided with a low pass filter 28 whereby the pulses 14a are substantially removed from the envelope thereby resulting in a substantially true reproduction 13b of the intelligence transmitted from source 1 as indicated by graph 2d.

Where the composite carrier according to graph 3a is received, the output of the clipper gate 23 is applied through switch 26 to an FM demodulator 29 of known character whereby the intelligence of source 2 is obtained from the clipped energy 30, graph 3c.

The outputs of the demodulators 22, 28 and 29 are applied to their respective reproducers.

While the two carriers produced in the system shown in Fig. 1 are mixed before transmission, it will be clear to those skilled in the art that the mixing may take place in the transmitting medium such as the ether, or if a line communication is used, at inbranching points along the line. To make this clear, Fig. 4 has been added showing a transmitter 31 whereby a carrier may be transmitted which is continuously modulated according to AM or FM modulating principles. A second transmitter 32 is shown, which is spaced from and otherwise independent of the transmitter 31, for transmitting a pulse modulated carrier. The two carriers thus transmitted mix in the ether and appear at receivers as a superposition composite carrier as indicated by graphs 2a and 3a.

While we have shown and described particular apparatus of the invention, it should be understood that such is given by way of illustration of the invention only and not as restricting the invention as set forth in the object and the appending claims.

We claim:

1. A method of multichannel communication comprising amplitude modulating a carrier wave of a given frequency with a continuous wave signal representing the intelligence from one signal source, modulating a second carrier wave of substantially the same frequency with a train of time modulated pulses representing the intelligence from a second signal source, superposing and simultaneously transmitting both modulated carrier waves, receiving the superposed carrier waves on a single receiving channel, separating the pulses from the received energy by clipping the received energy at a level above the maximum amplitude of the continuous wave modulation, and separating the continuous wave modulation from the received energy by clipping the received energy between two levels containing a substantial portion of the continuous wave modulation and a minimum, if any, of said pulses.

2. A system for multichannel communication comprising a source of continuous wave signals representing intelligence, a source of time modulated pulses representing other intelligence, means for simultaneously producing a plurality of carrier waves of substantially the same frequency, means for amplitude modulating one of said carrier waves with said continuous wave signal, means for modulating a second of said carrier waves with a train of said time modulated pulses, means for superposing and simultaneously transmitting both modulated carrier waves, a receiver for receiving the superposed carrier waves on a single receiving channel, a clipper biased to clip the received energy at a level above the maximum amplitude of the continuous wave modulation, and a gate clipper biased to clip the received energy between two levels containing a substantial portion of the continuous wave modulation and a minimum, if any, of said pulses.
